 Haughton Elevator Company, Toledo, Ohio, a
 corporation of Ohio

Application July 5, 1949, Serial No. 102,967

19 Claims. (Cl. 200—87)

1
 This invention relates to inductor switches and in particular to inductor switches that are operated by cooperation with a relatively movable magnetizable plate and that are arranged so that particularly at one end of the plate the switch is extremely sensitive to relative movement between the switch and the plate along a path parallel to the plane of the plate and insensitive to variations in spacing between the switch and the plate in a direction perpendicular to the plate.

Inductor switches have been proposed from time to time for use in controlling electrical circuits according to the position of a movable member such as an elevator car. These previously known inductor switches are suitable only for coarse indication of position because the position at which the switch contacts close as the member approaches a predetermined position differs materially from the position at which the contacts open as the member recedes from the fixed position. There is thus an appreciable zone of movement within which the contacts remain closed if closed and open if open. In this respect these inductor switches perform much the same as a toggle operated switch that depends upon the overcenter action of a spring to rapidly move the contacts from open to closed position or vice versa. Another difficulty encountered with most if not all inductor switches is that if the switch is arranged to cooperate with a plate of appreciable length the relative position at the end of the plate at which the switch operates varies with the transverse spacing between the switch and the plate.

The principal object of this invention is to provide an inductor switch that is suitable for cooperation with a magnetizable plate of considerable length in the direction of relative movement between the switch and the plate, which switch is arranged to be, particularly at one end of the plate, extremely sensitive to relative movement along the length of the plate and insensitive to movement perpendicular to the plate.

Another object of the invention is to provide an inductor switch that cooperates with a magnetizable plate and that opens and closes its contacts at substantially the same relative position between the switch and the plate whether the switch is approaching or receding from the plate.

A still further object of the invention is to provide an inductor switch suitable for operation with a magnetizable plate of appreciable length and capable of operating without appreciable uncertainty at a definite relative position between

2
 the plate and switch regardless of appreciable variation in spacing perpendicular to the path of relative movement.

More specific objects and advantages are apparent from the following description of several forms of improved inductor switches constructed according to the invention.

According to the invention the range of uncertainty observed in ordinary inductor switches is eliminated by arranging pivotally mounted magnetic pole pieces to extend like compass needles along the direction of the lines of force of the magnetic field and to be operated by changes in direction of the field. The position along the intended path of relative movement of the switch and plate at which the contacts operate is made substantially independent of transverse spacing between the switch and the plate by arranging the magnetic field to extend obliquely to such path from the magnet toward the approaching edge of the magnetizable plate. In this arrangement the pivoted pole pieces of the magnet are carried at the poles of the magnet to extend along and serve to concentrate the magnetic flux that follows a closed path from one pole of the magnet through the pivoted pole piece carried on that pole, across the gap to the side and edge of the magnetizable plate, through the plate and out the same side of the plate and across the gap to the other of the pivoted pole pieces and thence to the other pole of the magnet. Since the magnetizable plate is long in comparison to the space covered by the magnetic field the magnetic flux threading the pole pieces and extending across the gap spreads over a marginal area of the approaching plate that varies according to the spacing between the pole piece and the plate. By selecting the angle at which the magnet and pivoted pole pieces are placed with respect to the path of relative movement of the switch and plate the tendency of the field to spread and include a marginal area of the plate that varies with the spacing is utilized to maintain a fixed operating point along the path of movement regardless of variations in lateral spacing.

The improved switch may be advantageously employed as a leveling switch for passenger and freight elevators. In this use a plurality of switches preferably are mounted on the elevator car while magnetizable plates, one for each floor to be served by the car, are mounted in the elevator shaft preferably from the track that guides the car. The mounting arrangement may be reversed with the plate on the car and the switches

in the shaft. In the operation of a high speed elevator a number of controls are automatically called into action in stopping the elevator car and leveling it with respect to the floor being served. The sequence of control operations as the car approaches a floor includes first switching the car from the high speed running condition to a deceleration condition when the car is approximately 10 to 12 feet away from the floor being served. The deceleration characteristics are adjusted so that the car will be moving at fast approach speed when it is approximately 2 feet away from the floor. At this point one of the inductor switches mounted on the car comes opposite the magnetizable plate to establish the controls in the fast approach speed. This condition holds until the car is approximately 6 to 10 inches (the exact distance being varied by adjustment to suit the particular elevator) away from the floor when another inductor switch is operated by cooperation with the plate to call for slow approach speed. The car then decelerates until it is moving slowly so that it is ready to stop the instant the magnetizable plate leaves the first closed inductor switch thus permitting that switch to open. Should the car overrun, another inductor switch (normally operated if the car is approaching from the other direction) is energized to establish a reverse slow speed approach condition thus bringing the car back to the selected floor. A small "dead" zone is permitted between the opening of the first energized inductor switch and the closing of the reverse direction switch so that the car may come to a stop rather than be continuously moved first above and then below the selected floor. The successful operation of such a control depends upon the accuracy of operation of the inductor switches, particularly those that act to stop the car at the end of the slow speed approach. Previously known inductor switches because of their over-center effect have an uncertainty zone which adds to and thus objectionably extends the required dead zone with the result that it is practically impossible to maintain close leveling of the car with respect to the building floor. The improved inductor switches constructed according to the invention permit much more precise leveling than previously obtainable because they have no appreciable uncertainty zones to extend the dead zone and further because the position at which they respond to the magnetizable plate is, for over an appreciable distance, unaffected by horizontal movement of the car resulting from looseness or play between the rollers or shoes of the car and the guide rails.

Several examples of the improved inductor switches are illustrated in the accompanying drawings.

In the drawings:

Figure I is a simplified schematic illustration of an elevator car and fragments of the guide rails as well as structural members for supporting the magnetizable plate that cooperates with the inductor switch mounted on the car.

Figure II is a schematic illustration of one form of inductor switch constructed according to the invention.

Figure III is the same as Figure II except that it shows the effect of displacing the magnetizable plate laterally with respect to the inductor switch.

Figure IV is a diagrammatic illustration to show the principle of operation of another embodiment of the improved switch.

Figure V is the same as Figure IV showing the

effect of increasing the lateral spacing between the switch and plate.

Figure VI is a plan view of the structure of a switch constructed according to the switch illustrated in Figures II and III.

Figure VII is a side elevation of the switch shown in Figure VI.

Figure VIII is an end elevation of the switch as seen from the line VIII—VIII of Figure VI.

Figure IX is an end elevation of a modified form of switch embodying the invention.

Figure X is a plan view of the switch shown in Figure IX.

Figure XI is a sectional view, as seen from the line XI—XI of Figure X, showing the magnetic structure of the switch shown in Figures IX and X.

Figure XII is a detailed view as seen from the line XII—XII of Figure IX.

Figure XIII is a perspective view of a switch constructed according to the invention and schematically illustrated in Figures IV and V.

Figure XIV is an elevation with the case being shown in section of the switch illustrated in Figure XIII.

Figure XV is a section taken substantially along the line XV—XV of Figure XVI.

Figure XVI is a section taken along the broken line XVI—XVI of Figure XV.

These specific figures and the accompanying description are intended merely to illustrate the invention but not to limit its scope.

In an ordinary elevator construction a car 1 is supported by a plurality of cables 2 that are carried over sheaves of a driving motor at the top of the elevator shaft. The car is fitted with guide shoes 3 that run on tracks 4 secured to the walls of the elevator shaft. A control cable 5 depending from the bottom of the car carries the electrical conductors for the car controls such as floor selector buttons, floor indicating lights, leveling switch circuits, lights and other miscellaneous electrical connections. The tracks 4 are usually T-shaped in cross section with the guide shoes 3 running on the flange constituting the stem of the T-shape. A magnetizable plate 6 is mounted adjacent the path of the elevator car 1 and is supported on brackets 7 clamped to a frame member 8 and engaging an up-turned edge of the plate 6. The frame member 8 is shown as a separate member in the drawings whereas in actual construction it is customary to mount the magnetizable plates 6 from one of the tracks 4. A plurality of inductor switches 10, 11, 12 and 13 are mounted on the elevator car 1 in position to cooperate with the magnetizable plate 6.

As shown in the drawing the plate 6 has its ends rounded in the manner of a sled runner. This is to prevent catching and damage should the cases of the switches 10 or 13 strike the end of the plate.

The inductor switches 10, 11, 12 and 13, preferably of the type illustrated in detail in Figures XIII to XVI inclusive, are arranged in the control circuits for the car in substantially the same manner as were the mechanically cam operated switches previously used for elevator car control. The circuit and operation of these switches is such that if the car is approaching a floor from below, the switch 10 is first closed as it comes opposite the lower end of the magnetizable plate 6. The closing of this switch conditions the control for fast approach speed. As the car continues at fast approach speed, the inductor switch 11 closes as soon as it comes op-

posite the lower end of the plate 6 but this closing has no effect upon the control because ordinarily the switches 11 and 12 are connected in series. A moment later, when the car is about 6 inches from the desired stopping point, the switch 12 comes opposite the lower end of the plate and closes thereby completing the circuit conditioning the control for slow approach speed. This condition holds until the inductor switch 10 passes beyond the upper end of the plate 6 at which point this switch opens. The opening of the inductor switch 10 causes circuits to operate to immediately stop the car. Should the car overrun slightly the inductor switch 13, the bottom one on the series, is operated and it in conjunction with the now closed switches 11 and 12 conditions the car for slow speed approach in the downward direction to bring the car back to its proper stopping point. The dead zone, in which no circuits operate to cause the car to move, thus extends between a lower position at which the inductor switch 10 just closes and an upper position at which the inductor switch 13 just closes. The inductor switches 10 to 13 inclusive are adjustably mounted on the car so that a service man may easily adjust their positions relative to the magnetizable plate 6.

If it is desired to extend the slow speed approach zone the inductor switches 11 and 12 are moved closer together. If it is desired to extend the zone still further after the switches are brought practically into contact with each other they may be connected in parallel so that the first switch to operate then conditions the circuits for slow speed approach. This reverses the effect of the spacing of the switches so that still further lengthening of slow speed zone may be accomplished by moving the switches 11 and 12 further apart until finally they are brought adjacent the outside switches 10 and 13. If this is done a slow speed approach zone approximately equal in length to the length of the magnetizable plate 6 is provided. Normal operation, however, requires that the switches be connected in series since slow speed approach zones of 6 to 8 inches in length accommodate most elevator applications.

Inductor switches constructed according to the invention may take many forms. They may be arranged to operate entirely from one side of the magnetizable plate such as the inductor switches 10, 11, 12 and 13. They may also be arranged in interconnected pairs with the magnetizable plate passing between the pivoted pole pieces of each pair. This latter construction is illustrated schematically in Figures II and III and switches constructed according thereto are shown in detail in Figures VI to XII inclusive. Referring particularly to Figures II and III, which are the same except for the position of a magnetizable plate or vane 14 with which the switches cooperate, the switches each comprise a pair of pole pieces 15 that are pivotally mounted from frame members 16 and 17. The pole pieces 15 are interconnected by a link 18 arranged so that the pole pieces are constrained to rotate in opposite directions. A contact 19 carried on the link 18 completes a circuit to a contact 20 when the magnetizable plate 14 enters the zone between the free ends of the pivoted pole pieces 15.

The magnetic structure is arranged such that the pole pieces 15 have the same polarity and thus in the absence of the plate 14 tend to repel each other thereby opening the contacts and

holding them in open condition. As the plate 14 enters the region between the pole pieces the lines of force of the magnetic field bridge the gap between the tips of the pole pieces 15 and the adjacent marginal areas of the plate 14. The magnetic lines of force or flux lines spread over a marginal area of the plate that varies according to the distance to the plate and the orientation of the plate in the field. In the position indicated in Figure II, the position at which the contacts are just ready to close upon continued downward movement of the plate 14, the resultant magnetic pull of the magnetic field extends along a line through the pivoting axis of pole pieces 15 the pole tips of the pole pieces and intersects the side of the plate 14 at a small distance from the lower edge thereof. As the plate moves downward the flux continues to concentrate in the marginal area of the plate and the pole pieces 15, like compass needles, continue to point toward that area and thus rotate on their pivots as they follow the movement of the plate. Regardless of which direction the plate moves the pole pieces immediately follow because they are positioned by the direction of the magnetic field rather than by changes in the intensity of such field. As long as the plate 14 is equally distant from the pole pieces 15 the flux entering its sides is equally distributed.

In the event that the plate 14 is displaced laterally from its mid-position the operating point of the contacts 19 and 20 is not materially changed. This condition is illustrated in Figure III and the reason that the operating point is not affected is because the marginal area on one side of the plate 14 covered by the magnetic flux shrinks as the plate approaches one of the pole pieces and the covered area on the other side enlarges as the plate leaves the other pole pieces. Since the position of the pivoted pole pieces 15 depends upon the resultant of all the lines of force the pole pieces are aligned with the resultants of the flux fields regardless of where the resultant flux intersects the plate. Thus as the plate is displaced toward the left in Figure III, the marginal area covered by the flux on the left side of the plate decreases and the effective center of the field is nearer the bottom edge of the plate. Likewise on the right hand side the flux spreads over a larger area and its center moves upward away from the edge of the plate.

By proper selection of the angle of the pole pieces relative to the path of movement of the plate and the spacing between the pole pieces and the plate it is possible to find an operating point at which the change in marginal area covered by the flux varies at such a rate that the resultant force at the pivoted poles is independent of horizontal position of the plate. This particular construction, because of the duplication of magnets and pole pieces on each side of the plate, has a rather wide tolerance on the lateral position of the plate.

Substantially similar results may be obtained by a single magnet inductor switch such as is schematically illustrated in Figures IV and V. In this construction, which is typical of the inductor switches 10 to 13 inclusive, a pole piece 21 is pivotally mounted on the end of a magnet pole 22. The magnetic flux from the magnet after threading through the pole piece 21 establishes a field that cooperates with a plate 23 for producing limited rotary movement of the

pole pieces 21 to operate contacts 24 connected thereto.

In this arrangement the pole piece 21 acts as a compass needle in aligning itself with the magnetic lines of force extending from the magnet pole 22 through the pivoted pole piece 21 across the air gap and into the plate 23. The movement of the pole pieces is produced by changes in direction rather than strength of the magnetic field extending beyond the pole pieces and linking with the plate. Since the magnetic field enters the plate angularly from the side it tends to spread over a marginal area that varies with the separation between the pole pieces 21 and the plate 23 as measured in a direction perpendicular to the plate. Since the pivoted pole piece 21 tends to align itself with the field it points toward the magnetic center of the marginal area on the side of the plate 23. Since this magnetic center varies in position from the edge of the plate, moving up on the plate as the plate moves laterally away from the pole piece, it is possible to select an angular orientation for the magnet and pivoted pole piece 21 with respect to the path of relative movement of the plate so that the magnetic field at the tip of the pole piece 21 does not vary in direction with lateral movement of the plate. This is illustrated in Figures IV and V which are identical except for the spacing between the tip of the pole piece 21 and the plate 23. Thus when these members are relatively close together the magnetic flux entering the plate 23 is concentrated in the side of the plate near the lower edge thereof so that the pole piece tries to point directly toward the center of this area. As the plate is moved back as indicated in Figure V the flux entering the side of the plate spreads over a larger marginal area with the resultant center of the flux located substantially further from the edge of the plate. The operating position of the pole piece 21 and contacts 24 may therefore be selected so that without movement of the pole piece the pole piece continues to point toward the center of the marginal area of plate covered by the magnetic flux as the vane is moved laterally with respect to the pole piece. In general the pivoted poles and magnetic field to secure this independence of contact operation with lateral movement of the vane should be oriented approximately 45° from the path of relative movement between the inductor switch and plate. However, depending upon the actual configuration of the pole tips and the end of the plate it may be desirable to increase the angle so that the pole pieces are more nearly perpendicular to the plate in their contact operating position. In this connection it might be mentioned that the provision of "sled runner" ends on the vane as indicated in connection with Figure I may make it desirable to modify the shape of the ends of the pivoted pole pieces to provide satisfactory operation.

In each form of switch constructed according to the invention the pivoted pole pieces are counterbalanced so that they are in substantially neutral equilibrium and are thus not affected by acceleration or vibration of the elevator car on which they may be mounted. In each form of construction the pivoted pole pieces in at least one operating position are aligned with the magnetic flux so as to operate as compass needles in aligning themselves with the magnetic flux rather than as solenoid armatures that move in the direction of the field to shorten the magnetic path.

It is this shortening of the magnetic path with movement of the armature of a solenoid or relay that introduces the uncertainty of positioning making inductor switches so operated unsuitable as precision leveling switches.

This feature of operating the pole pieces in the manner of compass needles and orienting the pole pieces so that in operating position they are directed obliquely toward the magnetizable plate makes the operating position of the pole pieces practically independent of the strength of the magnetic field so long as the magnet strength is sufficient to overcome the frictional resistance of the mounting for the pole pieces. The change in magnet strength may result from changes in the magnet structure itself or from variations in the spacing between the pole pieces and the path of the magnetizable plate.

An inductor leveling switch suitable for use with an elevator car and constructed according to the principles illustrated in Figures II and III is shown in Figures VI, VII and VIII. This switch comprises a frame 25 mounted on the elevator car or other body the position of which is to be indicated. A pair of frame arms 26 extend from the frame 25 transversely to the path of movement of the body. In an elevator car for example the arms 26 are positioned horizontally. Permanent magnets 27 are rigidly clamped as by means of clamps 28 to the frame arms 26 and extend parallel to these arms. Each of the magnets 27 serves to magnetically energize a generally C-shaped frame comprising pole pieces 29 and 30 rigidly interconnected by a non-magnetic bar 31 and carrying magnetizable pole extensions 32. These C-shaped frame assemblies are pivotally supported on cone-pointed screws 33 that engage the pole pieces substantially in line with the ends of the magnets 27. The magnets 27 are oriented so that adjacent ones of the pole piece extensions 32 have like polarities and thus tend to repel each other.

Referring to Figure VIII each pair of C-shaped pole piece assemblies are interconnected by a linkage 35 so that the assemblies move in opposite directions and in generally equal amounts during the passage of the magnetizable plate 34 therebetween. When the plate 34 occupies the position shown in Figure VIII the upper pair of pivoted pole piece assemblies rotates to a position tending to separate the contacts of an electrical switch 36 operatively connected to the linkage 35. In the position shown the magnetic flux from the magnets 27 threading across the air gap from the pole pieces to the plate 34 induces magnetic poles in the magnetizable plate 34 of opposite polarity so that attractive forces are set up tending to pull the pivoted pole extensions 32 toward the adjacent edge of the plate 34. When the plate is in the position shown these attractive forces urge the upper right hand pole piece in a counter-clockwise direction and the upper left hand pole piece in a clockwise direction thus tending to move the linkage 35 toward the right to separate the contacts. As the magnetizable plate 34 moves upwardly relative to the upper set of magnets and pole piece assemblies (which also occurs upon downward movement of the inductor switch assembly) the pole extensions 32 continue to point toward the nearer edge, the upper edge, of the plate 34 rotating on their pivots in following the movement of the plate and thereby moving the linkage 35 to the left to close the contacts.

The contacts remain closed as long as the plate 34 is between the pole piece extensions 32. As

the plate moves still further and passes beyond the extensions a point is finally reached at which the repulsive forces between the pole piece extensions 32 overcome the attractive forces and the pole pieces then rotate to separate the contacts. Action at this second position may be referred to as operation of the contacts in the non-sensitive cooperative position between the switch and plate because in this cooperative relation the pole pieces do not point toward the area of the plate linked by the magnetic flux. In this latter condition the flux is generally along the path of movement of the pole piece extensions and they operate as ordinary relay armatures.

The lower pair of magnets and inductor switch pole piece assemblies 29a are similar in arrangement and operation to those just described except that the magnets are oppositely polarized. This opposite polarization is preferable although not necessary. By oppositely polarizing the lower set of magnets in relation to the upper set as seen in Figure VIII the pole piece extensions 32a of the lower set are repelled from each other while they are attracted toward the pole piece extensions of the upper switch assemblies thus insuring that the electrical switches remain open whenever the magnetizable plate 34 is absent.

This switch is practically immune to small lateral misalignment of the magnetizable plate 34 because of two effects. The first of these is that the flux linking with the plate tends to spread over a marginal area that varies with the lateral displacement of the plate so that the pole pieces in operative position point toward the center of such marginal area. The second effect is produced by the linkage 35 which equalizes the movement of the pole pieces.

Another embodiment of the invention is illustrated in Figures IX and XII inclusive. In this embodiment standards 37 erected from an elevator car or other member support a U-shaped housing 38. The inductor switch mechanism is mounted within the U-shaped housing while a magnetizable plate or vane 39 is arranged to pass through the opening of the housing 38 as it cooperates with the switch. The switch elements themselves comprise permanent magnet bars 40 that are clamped to a bracket 41 mounted within the housing 38. Pole pieces 42 (see also Figure XII) are pivotally mounted on the sides of the magnets 40 one near each end of each of the magnets. The pivoted pole pieces 42 on each magnet are connected by a C-shaped frame 43 that also carries a balance weight 44 so that the pivoted pole pieces are in substantially neutral equilibrium and thus able to readily respond to any magnetic forces tending to rotate them around their pivoting axes. In addition, the C-shaped frames 43 are each provided with a laterally directed lug 45 to which a link 46 is pivotally connected. The link 46 serves to equalize the movement of the pivoted pole pieces as well as to carry one contact 47 of an electrical switch 48.

As is clearly indicated in the drawings, the pivoted pole pieces 42 extend obliquely toward the path of relative movement between the plate 39 and the inductor switch. As the plate 39 moves into the space between the ends of the pivoted pole pieces 42 the pole pieces move toward each other thus closing the switch 48 operatively connected to the pole pieces 42 through the link 46. Furthermore the magnets 40 are oriented with like poles adjacent each other so that in the absence of the plate 39 the pivoted pole pieces 42 repel each other to open the switch contacts.

This switch, like the one previously described, provides high sensitivity to relative movement of the plate 39 when the plate is approximately in the position shown. This high sensitivity with freedom from uncertainty in operating position results because the contact operation is produced by a compass needle like action of the pole pieces as they point toward the lower marginal areas of the sides of the plate 39. In this arrangement there is no change in length of the magnetic path produced solely by movement of the pivoted pole pieces. Thus the operating position of the switch is the same whether the magnetizable plate be moving toward or away from the pole pieces at the position shown in Figures IX to XI inclusive. As long as the plate 39 is below the position shown the contacts will obviously be closed while if it is at or above the position shown the contacts are open.

In this example as in the preceding example lateral displacements of the magnetizable plate 39 do not materially alter the position along the path of relative movement at which the contacts are operated. This result follows because of the link 46 connecting the pole pieces as well as because of the fact that the pole pieces point toward an effective center of each marginal area of the plate that varies in height on the plate according to the lateral displacement of the plate. Again by proper selection of the angular position of the pole pieces to which the contacts are operated it is possible to make the switch practically immune to lateral misalignment.

Switches constructed according to this second example are used in pairs to cooperate, in their sensitive positions, one with the upper edge of the magnetizable plate and the other with the lower edge. Thus two of these switches are required to perform the same function as that performed by the complete switch shown in the preceding example.

In the two examples just described magnets and pole pieces are arranged on both sides of the cooperating magnetizable plate. While this arrangement provides some advantage because of the compensation resulting from increasing the spacing of the plate from one set of pole pieces while the spacing from the other set is decreased, satisfactory operation of an inductor switch may be obtained with a structure that is essentially one-half of the arrangement shown in this second embodiment (Figures IX to XII). Such a switch with some modifications is illustrated in Figures XIII to XVI inclusive.

This construction, which is preferred because of its simplicity both in construction of the switch itself and in its mounting for use, comprises a generally cubical case 50 constructed of brass or other non-magnetic material. One side of the case has an insulating strip 51 through which terminal leads are taken and another side of the case has a window 52 through which the operation of the contacts may be observed. The mechanism of the switch itself is mounted from a stainless steel or other hard non-magnetic plate 53 which serves as a cover for another side of the cubical case 50. This switch is designed to cooperate with a magnetizable plate 54 a fragment of which is shown in Figure XIV. The end of the plate 54 may be either straight or bent as shown to provide a sled runner effect so that the plate cannot catch on the corners of the case if an excessive amount of misalignment should occur.

The operating mechanism of the switch itself,

contained within the cubical housing 50, is mounted from a bracket 55 which for convenience in assembly is attached to the cover plate 53. The mechanism comprises a U-shaped permanent magnet 56 that is arranged at an angle to the path of relative movement between the switch and the magnetizable plate 54. On the pole faces of the magnet 56, which are directed toward the nearer end of the plate 54 when the plate is in sensitive contact operating position as shown in Figure XIV, are pivotally mounted a pair of pole pieces 57 that are furthermore rigidly interconnected by a generally T-shaped non-magnetic plate 58. The pole pieces 57 are mounted near the ends of the cross bar of the T-shape.

The magnet 56 and the contact mechanism of the switch are mounted from a non-magnetic support plate 59 the magnet being clamped thereto by a pair of bolts 60 that extend through a fiber block 61, through the bight of the magnet 56, through the mounting plate 59 and through the bracket 55. The fiber block 61 which may be of "Bakelite" or other insulating material serves as a base for the stationary portions of the switch mechanism. The moving part of the switch is carried on the T-shaped plate 58 and more particularly from the stem of such plate.

The stationary parts of the electrical contacts of the switch include a generally Z-shaped arm 62 that is secured at one end of the fiber block 61 by means of a bolt 63 that also serves as an electrical connection to an incoming lead 64 which in turn is connected to an external terminal 65 (see Figure XIV). The free end of the Z-shaped bracket carries an adjustably mounted contact 66 that cooperates with contacts carried on a leaf 67 constituting the moving arm of the switch. A second stationary contact 68 is adjustably mounted from a small metallic plate 69 which in turn is secured to the fiber block 61 by an attaching bolt 70 serving as a connection for a lead 71 the other end of which is attached to an external terminal 72 of the complete switch assembly.

The movable switch plate 67 is secured to a fiber block 73 mounted on the side of the stem of the T-shaped plate 58 carrying the pivoted pole pieces 57. A flexible "pig-tail" lead 74 is connected between the mounting bolt 70 holding the second stationary contact and a screw 75 that serves to secure the moving switch leaf 67 to the fiber block 73. Thus the second stationary contact is always electrically connected to the moving switch arm and therefore serves merely as an adjustable stop to limit the travel of the switch arm in a direction away from the first fixed contact 66 which is mounted on the end of the Z-shaped arm 62.

A piece of thin spring wire 76 one end of which is held under one of a number of screws 77 attaching the pivoted pole pieces 57 to the T-shaped plate 58 has its other end loosely fitted through a transverse hole in a stud 78 adjustably mounted in the fiber block 61. The forces exerted by this spring 76 are very small in comparison with the magnetic forces involved when the inductor switch cooperates with the magnetizable plate 54. The function of the spring 76 is to provide a small force tending to move the pivoted pole pieces and T-plate assembly to separate the movable contact leaf 67 from the first fixed contact 66 so that the switch is open when it is not under the influence of a magnetizable plate.

Furthermore, so that acceleration forces, which may be applied to the switch because of the move-

ment or vibration of the member upon which the switch is carried, shall not cause false operation of the switch the T-shaped plate 58 is provided with a balance weight 79 of such size and location that the assembly of pole pieces and T-shaped plate is in neutral equilibrium with respect to the pivoting axis of the assembly. This pivoting axis is defined by chisel-shaped edges 80 provided on the edges of the pivoted pole pieces 57 where they rest on the pole faces of the magnet 56.

To prevent derangement of the pole pieces with respect to the magnet a pair of non-magnetic U-shaped metallic strips 81 and 82 are attached to the non-magnetic mounting plate 59 with the up-turned ends of the U-shaped plate 81 serving as thrust plates cooperating with the corners of the pole pieces 57 at the inner ends of the chisel-shaped edges 80 to prevent movement of the pole pieces parallel to the pivoting axis. The other U-shaped strip 82 is provided with V-shaped notches the sides of which engage the chisel edges 80 of the pole pieces 57 to keep the pole pieces centered on the pole faces of the magnet.

In the construction of the pivoted pole pieces 57 the edges are beveled symmetrically from each side to form the chisel-pointed pivoting edges 80 so that the magnetic forces acting between the pole pieces and the pole faces are substantially symmetrical about the pivoting axis and thus do not bias the pole pieces in either direction.

If it were not for the precision required in manufacture it would be practical to disturb the symmetry of the chisel-shaped edges and locate the sharp edge off center so that the magnetic forces supply the small restoring force normally provided by the spring 76. In actual construction however the spring is preferable because not only is it easier to make but it may also be adjusted to compensate for inaccuracies in the formation of the chisel-shaped edges 80 and thus secure the proper biasing force for satisfactory operation.

It will be noted that the free ends of the pivoted pole pieces 57 are bent upwardly as seen in Figure XIV so as to extend for a short distance parallel to the path of relative movement between the inductor switch assembly and the magnetizable plate 54. This arrangement was selected to provide more positive operation of the switch and to compensate for the sled runner ends of the magnetizable plate 54.

These inductor switches are normally employed in the arrangement illustrated in Figure I there being four of the switches mounted on each elevator car with two of the switches serving as final leveling position controls and the other two serving to control the changeover from fast approach speed to slow approach speed. Identical switches are used in all four positions even though the superior operating characteristics of the improved switch are required only in the two switches determining the final leveling position. The improved switch as illustrated in Figure XIII to XVI inclusive is simple enough in construction that it is more economical to standardize on this particular switch than to carry two types of switches, one for final leveling and the other for approach control.

In reference to Figures I and XIV it will be noted that the relative position of the inductor switch assembly and the magnetizable plate 54 as shown in Figure XIV is reached when the elevator car is level with the floor. In arriving at this position one of the switches has just

passed through its zone of cooperation with the magnetizable plate while the other of the co-operating switches has just failed to reach its zone of cooperation. The operation of the switch may be understood by considering that the switch assembly illustrated in Figure XIV is mounted in a position corresponding to the switch 13 of Figure I. Assuming that the car is approaching the desired floor from a higher floor, the first cooperation between the pivoted pole pieces 57 and the magnetizable plate 54 occurs when the upper end of the plate 54 (marked 54') is approximately in the position shown by the dotted line position in Figure XIV. In this position the magnetic field extending from the pole pieces to the magnetizable plate is substantially parallel to the path of movement of the ends of the pivoted pole pieces. As a result the operating point of the switch, which is operated by counterclockwise movement of the pole pieces, varies with the lateral spacing of the magnetizable plate from the switch assembly. This is of no material disadvantage because this operating position is not critical in the control of the elevator car. This relative position and switch operation occurs at a point about two feet from the final leveling position. This switch operation merely conditions the controls to insure that the car is moving at fast approach speed in the zone extending between points spaced approximately two feet and about six inches from the final leveling position. As the car continues downwardly and the magnetizable plate 54 appears to move upwardly with respect to the switch assembly it finally reaches the relative position shown by the solid lines in Figure XIV. In this position the pivoted pole pieces 57 have rocked clockwise to open the contacts of the switch. In this cooperation the pole pieces are very sensitive to movement of the magnetizable plate in a vertical direction as shown in the figure and have no appreciable uncertainty zone since they point, like compass needles, toward the magnetizable plate to follow every minute movement of the plate. In this position of cooperation the contacts may be positively made or broken by one thirty-second of an inch movement of the elevator car. Furthermore by careful selection of the angular position of the magnet and pole pieces, having in mind the compensation required by the sled runner effect on the end of the magnetizable plate 54, the tendency of the magnetic flux to spread over the lower marginal area of the magnetizable plate is employed so that the plate may move laterally in either direction from the position shown without causing movement of the pivoted pole pieces. This condition obtains for a horizontal variation in spacing that is appreciably greater than the total horizontal movement of the elevator car that may occur through slack or looseness in the fittings of the guide shoes or rollers connecting the car to the guide tracks.

This improved inductor switch while relatively simple of construction and design is nevertheless capable of providing a precise indication of relative position of a pair of relatively movable members and of indicating that position accurately regardless of much larger movements in transverse directions. Furthermore it has the advantage that the indicated position is independent of the direction of relative movement by which that position is approached.

Various modifications in detail of construction

of inductor switches employing obliquely-directed pivoted pole pieces cooperating with the marginal area of a magnetizable plate may be made without departing from the spirit and scope of the invention.

Having described the invention, I claim:

1. An inductor switch for generating signals for controlling the relative position of one member with respect to another member through an extended zone of relative movement which switch at one end of the zone is sensitive to relative movement of said members along the intended path of movement and insensitive to relative movement transverse to said intended path, comprising in combination, a magnetizable plate included in one of the members, said plate being parallel to the path of relative movement and generally equal in length to said zone, a magnet assembly included in the other member, said assembly comprising a magnet and a pole piece pivoted at a pole of the magnet, said pole piece being directed obliquely toward said plate, and extending generally along a line from the magnet pole to the marginal area at the end of the plate as the magnet assembly passes beyond the sensitive end of the zone.
2. An inductor switch for energizing positioning controls according to the presence within an extended zone of a first member with respect to a second member, which switch particularly at one end of the zone is sensitive to relative movement of the members along the length of the zone and insensitive to movement transverse to the length of the zone, comprising, in combination, a magnetizable plate included in one of the members, said plate being located along the path of relative movement of the members and generally equal in length to the zone, a magnet assembly including magnet and a pole piece pivoted at a pole of the magnet, said pole piece being directed obliquely to the path of relative movement of the members and toward the marginal area of the plate as the magnet assembly passes beyond the sensitive end of the zone, said magnet assembly and magnetizable plate producing a magnetic field that spreads with increasing transverse separation of said members to cover a larger marginal area of said plate and maintain generally unchanged the oblique direction of the field about the end of the pole piece.
3. An inductor switch for signalling throughout an extended zone of relative movement the relative position of a first member with respect to a second member, which switch at the end of the zone has high sensitivity to relative movement along the zone and low sensitivity to movement transversely of the zone, said switch comprising, in combination, a magnetizable plate on one of the members and a magnet assembly on the other of the members, the assembly including a magnet and pivoted pole piece, the switch being characterized by having the pole piece of the assembly pivoted at a pole of the magnet and extending obliquely to the path of relative movement along the line of action of the magnetic field as it links with the marginal area of the magnetizable plate during the time that the magnet assembly is located just beyond the end of the plate.
4. An inductor switch that is actuated by cooperation with a relatively movable magnetizable plate, said switch comprising a magnet for establishing a magnetic field, and a pole piece pivoted at a pole of the magnet for operating electrical contacts, said switch being characterized by hav-

ing the contact operating position of the pivoted pole piece oriented obliquely to the path of relative movement of the magnetizable plate and in line with the magnetic field that, when the switch is just beyond the end of the plate, links with the marginal area of the end portion of the plate.

5. An inductor switch which is actuated by magnetic cooperation with a relatively movable magnetizable plate and which at one end of the zone of cooperative positions of the switch and plate is sensitive to relative movement lengthwise of the plate and insensitive to movement perpendicular to the plate, said switch comprising a magnet for establishing a magnetic field and a pole piece pivoted at a pole of the magnet and arranged to operate electrical contacts, said pole piece in contact operating position being oriented obliquely to the plane of the plate and the path of relative movement so as to point toward the nearer marginal area of the plate and to rotate through a small angle as the plate moves relative to the switch so as to continue to point toward such area as the plate approaches or recedes from the switch.

6. An inductor switch that is actuated by magnetic cooperation with a relatively movable magnetizable plate extending parallel to the path of relative movement of the switch and plate, said switch being characterized by having contact operating pole pieces pivotally mounted at the poles of a magnet of the switch and extending obliquely to the path of relative movement of switch and plate in alignment with flux passing from the pole pieces to the plate.

7. An inductor switch that is actuated by magnetic cooperation with a relatively movable magnetizable plate extending parallel to the path of relative movement of the switch and plate, said switch comprising a magnet, pole pieces pivoted for limited rotation about the pole tips of the magnet, and cooperating electrical contact elements one of which is operatively connected to the pole pieces and the other of which is fixed with respect to the magnet, said switch being characterized by having the pivoted pole pieces oriented along the lines of force of the magnetic field and obliquely to the path of relative movement of the switch and plate, whereby the pole pieces are predominantly responsive to changes of direction of the magnetic field as the switch enters and leaves the zone of cooperation with the magnetizable plate.

8. An inductor switch that is actuated by magnetic cooperation with a relatively movable magnetizable plate extending parallel to the path of relative movement of the switch and plate, said switch comprising a pair of magnets, a set of pole pieces pivotally mounted for limited rotation at the poles of each magnet, said magnets and pole pieces being located on opposite sides of and oriented obliquely to the path of the plate, a linkage interconnecting the sets of pole pieces, and cooperating electrical contacts one of which is operatively connected to the pole pieces and the other of which is fixed with respect to the magnets.

9. An inductor switch that is actuated by magnetic cooperation with a relatively movable magnetizable plate extending parallel to the path of relative movement of the switch and plate, said switch comprising a frame extending to each side of the plate, a pair of magnets fixedly mounted in the frame, pole pieces pivotally mounted at each pole of the fixedly mounted magnets, linkage interconnecting pole pieces on opposite sides

of the plate, and cooperating electrical contacts one of which is operatively connected to the linkage and the other of which is fixed with respect to the magnets, said switch being characterized by the orientation of the pole pieces which being directed obliquely to the path of relative movement are in alignment with the magnetic field from the magnets to the marginal area of the plate when in contact operating position.

10. An inductor switch that is actuated by magnetic cooperation with a relatively movable magnetizable plate extending parallel to the path of relative movement of the switch and plate, said switch comprising a frame, a magnet mounted on the frame, pole pieces pivotally mounted at the pole faces of the magnet and extending as continuations of the magnet poles in a direction oblique to said path of relative movement, and electrical switch contacts one of which is operatively connected to the pole pieces and the other of which is fixed with respect to the magnet, said switch being characterized by the oblique orientation of the pole pieces such that in contact closing position the pole pieces are aligned with the magnetic field extending from the pole faces to the marginal area of the plate.

11. In an inductor switch device for energizing control circuits according to the presence of a body within a prescribed zone, in combination, a magnetizable plate extending along the zone, a magnet mounted on the body, pole pieces pivotally mounted at the pole faces of the magnet and extending obliquely toward the plate, cooperating electrical contacts one of which is operatively connected to the pole pieces and the other of which is fixed with respect to the magnet, said pole pieces extending in alignment with the magnetic field and being directed toward the marginal area of the plate as the first approaching edge of the plate approaches juxtaposition to the switch.

12. In an inductor switch device for signaling the presence of a body within a prescribed zone, in combination, a magnetizable plate extending along the zone, a magnet mounted on the body with the poles of the magnet directed obliquely toward the plate, pole pieces pivotally mounted at the pole faces of the magnet and extending along the field of the magnet and cooperating electrical contacts one of which is operatively connected to the pole pieces and the other of which is fixed with respect to the magnet, said contacts and pole pieces being oriented and arranged to operate in response to relative movement between switch and plate when the marginal area of the plate is in alignment with the obliquely extending pole pieces.

13. In an inductor switch device for signaling the presence of a body within a prescribed zone, in combination, a magnetizable plate extending along the zone, a magnet mounted on the body with the poles of the magnet directed obliquely toward the plate, pole pieces pivotally mounted at the pole faces of the magnet and extending along the field of the magnet toward the plate, said pivoted pole pieces each having an extended end that is generally parallel to the plane of the plate, and cooperating electrical contacts one of which is operatively connected to the pole pieces and moved to contact with the other by rotation of the pole pieces as they continually point toward the approaching marginal area of the magnetizable plate as that edge approaches the switch.

14. In a magnetic induction switch, in combi-

17

nation, a magnetizable plate mounted on a first member, a magnet mounted on a second member, said magnet providing a magnetic field that is adapted to link with the magnetizable plate and which field extends obliquely to the path of movement of the member to link with the nearer marginal area of the plate when the plate is approaching toward or receding from the switch, a pivotally mounted armature that is oriented to extend along the oblique position of said magnetic field linking the marginal area of the plate and that moves in response to changes in direction of the magnetic field as the plate moves relative to the magnet, and cooperating electrical contacts one of which is operatively connected to the armature to be operated as the armature moves in response to changes in direction of the magnetic field.

15. A magnetic induction switch according to claim 14 in which the magnet is U-shaped and its pole faces are perpendicular to the lines of force of the oblique field and the armature is pivoted at the pole faces of the magnet.

16. A magnetic induction switch according to claim 15 in which the armature has a knife edge opposed to the pole faces of the magnet and a counterweight of sufficient magnitude to secure a condition of neutral equilibrium in the armature and attached electrical contact.

17. A magnetic induction switch according to claim 14 in which the poles of the magnet are

18

separated along a line perpendicular to the path of relative movement and parallel to the cooperating magnetizable plate.

18. A magnetic induction switch according to claim 14 in which a second magnet and armature are positioned relative to the first magnet and armature to receive the magnetizable plate between the magnets and in which a linkage interconnects the armatures to assure simultaneous operation of the armatures.

19. A magnetic induction switch according to claim 18 in which the magnets have like poles opposed whereby the pivoted armatures are repelled from each other in the absence of the magnetizable plate.
